ELECTRIC SPACE-CHARGE DEVICE

Lester H. Smith, Maplewood, N. J.

Application October 1, 1943, Serial No. 504,531

6 Claims. (Cl. 204—312)

1

This invention relates to improvements in devices for creating an electric space charge within a volume of gas or vapor or within a suspension of liquid or solid particles in a gas. In particular this invention is concerned with the use of high frequency fields for increasing the effect of such electric space charges on the gases or suspended materials being processed.

The improvements proposed are particularly concerned with the methods of mechanically projecting electrically charged physical particles from emitting electrodes such as have been described in my copending applications No. 481,767 and No. 504,532 both now abandoned, and the combination of high frequency electrostatic and electromagnetic fields with the space charges so produced.

Considerable experimental work has been done in the treatment of various gases with high frequency electrostatic and electromagnetic fields. In the case of hydrocarbon gases, polymerization products and residual gases are usually obtained.

An object of the present invention is to combine the effect of an electric space charge and a high frequency field, on various gases or suspensions in gases containing the space charge. Theoretically, a high frequency electrostatic or electromagnetic field should bring about circulating currents due to the presence of the electric charges on the particles which are mechanically projected from the emitting electrode, as well as increased ionization and local electrolytic action throughout the gas or the suspension in a gas.

Other objects of this invention will be apparent from the drawings and the following description of the features of the invention and in the provision of apparatus and methods of operation for accomplishing the foregoing object.

In accordance with one modification of my invention, electrically charged physical particles are mechanically projected from an emitting electrode which may be a nozzle, a vibratory plate, or a rotating surface. Necessary electrostatic fields to induce the flow of electric charges on the projected particles are set up by a wide spaced grid electrode in close proximity to the emitting electrode and a collecting electrode located at a proper distance from the emitting electrode and maintained at such a direct current potential as to cause a drift of the charged particles toward the collecting electrode which also provides an external electrical return circuit to the emitting electrode. At the same time a flow of gas or of a gas containing a suspension is maintained through

2

the chamber or container housing these electrodes. In addition to the direct current potentials, a high frequency potential source is connected between the emitting electrode or grid electrode and the collecting electrode, using these same electrodes to produce a high frequency electrostatic field. The design of the electrodes, the path of the drifting space charge and the circulation of the gas or suspension in a gas are such as to obtain maximum processing effect.

In accordance with a second modification of my invention, electrodes for producing a high frequency electrostatic field which are separate from the electrodes used to produce the direct current electrostatic fields are used. This will be made clear in the discussion of the drawings.

In accordance with a third modification of my invention, a space charge is produced in the same manner as described in connection with the first modification, by the projecting of electrically charged physical particles from an emitting electrode in combination with a grid electrode and a collecting electrode. This space charge is passed through or in close proximity to a high frequency winding which generates a high frequency magnetic field. At the same time a flow of gas or of a gas containing a suspension is maintained through the same path traveled by the drifting space charge.

The circulation of the gas or suspension to be processed should preferably be parallel to the path of the space charge between the emitting and collecting electrodes. It may be counter-current with proper proportioning of direct current potentials and gas velocities.

It may be desirable to have the electrically charged physical particles projected from the emitting electrode, consumed or evaporated upon mixing with the gas or suspension to be processed, leaving the electric space charge available in a free state throughout the gas or suspension.

Throughout this specification and the accompanying claims I have used the expression—wide spaced or intermediate grid—to describe one of the electrodes involved in this invention. By this expression I mean any arrangement of wires, rods or plates which in combination with an emitting electrode and a collecting electrode may be used to produce unobstructed electrostatic flux lines directed from the emitting electrode toward the collecting electrode. Obviously, the wires or plates must have open spaces between them. For purpose of illustration, I have shown in the drawings wide spaced mesh grids constructed of parallel wires or plates.

Referring to the drawings,

Fig. 1 illustrates a preferred form of space charge device in which the same electrodes are used for setting up both the direct current electrostatic fields and the high frequency electrostatic fields.

Fig. 2 shows a modification of Fig. 1 in which the entering gas to be processed passes through the emitting electrode. Furthermore, separate electrodes are provided for setting up the high frequency electrostatic field.

In Fig. 3 is shown a preferred form of space charge device in which the drifting space charge and the gas or suspension circulating through the device are subjected to a high frequency electromagnetic field.

Fig. 4 shows a typical grid electrode used in the device of Fig. 3.

In Fig. 5 is illustrated an alternative arrangement of the high frequency electromagnetic winding of Fig. 3.

Figure 6 shows a form of rotating emitting electrode which can be utilized in either Fig. 1 or Fig. 3 in place of the vibratory emitting electrodes shown.

In Fig. 1, the vessel 1 is constructed of a non conducting material such as glass sections or impregnated wood. The vessel 1 is provided with a raw gas inlet 2 and processed gas outlet 3 and drain outlet 4. A flexible circular plate electrode 5 in the upper portion of vessel 1 is supported from insulating collar 23 and is connected to the lower end of the shaft 6 which is in turn connected to a source 7 of intermittent vertical vibratory motion of approximately 120 cycles per second. The plate electrode 5 is the emitting electrode and is supplied with a fluid used to form charged particles through the tube 8. The tube 8 passes downward through the top of vessel 1 and makes a right angle bend and runs horizontally close to the upper surface of plate electrode 5. The tube 8 has a slot 9 in the lower surface. A slot 10 is also provided in the plate electrode 5 close to the slot 9 in tube 8. In between the periods of vibration of emitting plate 5, additional fluid is supplied through tube 8 and slots 9 and 10 and runs downhill on the lower surface of plate electrode 5 covering the lower surface of plate electrode 5 with a thin film of liquid. This thin film is projected downward in the form of tiny droplets upon vibration of the plate electrode 5. A gas tight sleeve 11 in the top of vessel 1 permits vertical motion of the shaft 6. A wide spaced grid electrode 12 which is located close to the lower surface of emitting electrode 5 is provided, also a collecting electrode 13 in the form of a screen. Collecting electrode 13 is supported by an insulator 14 and insulating bushing 15 which provides an external electrical connection to electrode 13. An external electrical connection to grid electrode 12 is provided through insulating bushing 16. The emitting electrode 5 is connected to ground, as shown. The wide spaced grid electrode 12 is maintained at a direct current potential of around 800 volts relative to ground by means of potential source 17. The collecting electrode 13 is maintained at a direct current potential of around 1500 volts relative to grid electrode 12 by means of potential source 18. The electrical condenser 19 acts as an accumulator and facilitates the flow of electric charges between emitting electrode 5 and collecting electrode 13. Resistance 36 is for current limiting purposes in case of temporary liquid bridges grounding the electrode 12. A source 20 of high frequency current at about 50,000

cycles per second is connected to a primary coupling coil 21. A secondary winding 22 coupled with coil 21 introduces a high frequency potential in series between collecting electrode 13 and direct current potential source 18.

Operation of the device shown in Fig. 1 is as follows: a gas to be processed, such as propane, for example, enters through raw gas inlet 2, passes downward through collecting screen electrode 13 and leaves through processed gas outlet 3. The emitting electrode 5 projects a cloud of liquid particles, of liquid butane, for example, downward during periods of vertical vibration. These liquid butane particles carry an electric charge due to the direct current potentials of grid electrode 12 and collecting electrode 13. After passing downward through the wide spaced grid electrode 12, the charged butane particles mix with the propane gas entering through inlet connection 2. At the same time the electric charges carried on the particles are subjected to the high frequency electrostatic field set up between grid 12 and collecting electrode 13. Ionization and local electrolytic action take place throughout the circulating gas. Polymerization products resulting may be collected as condensate in the bottom of vessel 1 or they may be separated from the processed gas by means that do not form a part of this invention. Between periods of vibration of the emitting electrode 5, the lower surface of 5 is rewet with fluid fed through the tube 8. Residual electric charges are collected by electrode 13 and returned through the external circuit to emitting electrode 5.

In Fig. 2, the vessel 1 is also constructed of electrically non conducting material as in Fig. 1. Likewise, a raw gas inlet 2, a processed gas outlet 3 and drain outlet 4 are provided. An emitting electrode 5 is vibrated in a horizontal direction by shaft 6 which passes through the gas tight sleeve 11 and is connected to the source 7 of intermittent vibratory motion. The emitting electrode 5 is a circular flexible plate provided with perforations and is rigidly supported at the edges by the solid insulating collar 23. The emitting electrode 5 is supplied with fluid used to form charged particles through the tube 8 which makes a right angle bend and extends horizontally across the top of emitting electrode 5. A slot 9 is provided in the horizontal portion of tube 8 close to the surface of emitting electrode 5. In between periods of vibration of electrode 5 the fluid supplied through tube 8 and slot 9 runs down over the front surface of emitting electrode 5. The wide spaced grid electrode 12 and collecting screen electrode 13 are similar to those in Fig. 1 and function in the same manner except that they do not set up any high frequency electrostatic field. The parallel plate electrodes 24 and 25 are connected through insulating bushings 26 and 27 to the high frequency secondary winding 22. The source 20 of high frequency current and primary winding 21 are the same as in Fig. 1. The emitting electrode 5 is connected to ground. Direct current potentials 17 and 18 and electrical condenser 19 and resistance 36 are the same as in Fig. 1. The high frequency electrodes 24 and 25 are maintained at a negative direct current potential of about 150 volts relative to ground by potential source 39.

Operation of the device shown in Fig. 2 is very similar to that of Fig. 1. The gas or suspension of material in a gas to be processed enters through inlet 2, passes through the perforations

in emitting electrode 5 toward the grid electrode 12 and collecting screen electrode 13 and out through the processed gas outlet 3. At the same time, charged particles of the fluid supplied through tube 8 are projected from emitting electrode 5 through wide spaced grid electrode 12 and toward the collecting screen electrode 13. Circulating currents and electrolytic action in the mixture of charged particles and gas or the suspension to be processed is promoted by the high frequency electrostatic fields set up between electrodes 24 and 25.

In Fig. 3 the vessel 1 is constructed of electrically non conducting material as in Figures 1 and 2. Likewise, a raw gas inlet 2, processed gas outlet 3 and drain outlet 4 are provided. The arrangement of the emitting electrode 5, methods for supplying fluid to electrode 5 from which charged particles are to be formed and for vibrating the emitting electrode are identical with those used in Fig. 1. The wide spaced grid electrode 12 is also identical with that of Fig. 1 and serves the same purpose. In order to have the high frequency winding 28 at a proper distance from the emitting electrode and to avoid excessive circulating currents in the emitting electrode, it is necessary to make use of several intermediate grid electrodes 29 and 30. These intermediate grid electrodes as well as the collecting screen electrode 13 are shaped as shown in Fig. 4 so as to discourage circulating currents. The direct current potentials 31, 32 and 33 which are used between the various grid electrodes and the collecting screen electrode 13 are dependent upon the dimensions of the apparatus and gas velocities through the device. The high frequency winding 28 passes completely around the vessel 1, as shown, and is supplied with high frequency current from the source 20 at a frequency of about 50,000 cycles per second. Items 15, 16, 31 and 33 are insulating bushings.

Operation of the device shown in Fig. 3 is as follows: The gas to be processed, such as propane, for example, enters through the raw gas inlet 2 and mixes with the electrically charged particles, of liquid butane, for example, which are projected downward from the lower surface of electrode 5, as in Fig. 1. The mixture of charged butane particles and propane gas travels downward through the intermediate grid electrodes 29 and 30. As this mixture passes through the high frequency electromagnetic field set up by the winding 28, circulating currents are produced throughout the mixture, resulting in increased ionization of the gas or suspension and local electrolytic action. Residual electric charges equal to those leaving the emitting electrode 5 are collected on the screen electrode 13 and are returned through the external circuit shown to the emitting electrode 5. Polymerization products resulting may be collected in the bottom of vessel 1 or may be separated from the processed gas leaving through outlet 3 by a separate condenser not shown.

The alternative arrangement shown in Fig. 5 of the high frequency winding used in Fig. 3 consists merely of directing the electromagnetic field across the path of the charged particles and gas by splitting the winding into two halves 34 and 35. Other parts of the device remain the same as in Fig. 3.

In Fig. 6 is shown an alternative arrangement with a rotating emitting electrode which can be used in place of the vibratory emitting electrodes shown in Figures 1 and 3. A partial section only

is shown in which item 1 is the wall of the vessel, 11 is a gas tight insulating bushing which allows rotation of a shaft 6 and a disc emitting electrode 5. Item 40 is a motor which turns shaft 6 at approximately 200 R. P. M. Tube 8 feeds fluid material to the top surface of disc 5 which material is projected in the form of fine particles from the edge of disc 5 and falls through the openings in the wide spaced or intermediate grid electrode 12. Item 16 is an insulating bushing.

In Figures 1 and 3, I have shown electrical connections for creating space charges of negative polarity. Reverse connections of the potential sources used will create positive space charges just as readily as negative ones. Also, the size of the potentials applied between the various electrodes and the rate of vibration or rotation of certain emitting electrodes are not critical but can be varied as desired.

With regard to the electrical processing of suspensions in gases, it is contemplated that certain materials in a finely divided state may be suspended in a gas in order to be able to process them in this manner. The gas present may or may not enter into the reaction or change of state which it is desired to accomplish.

As mentioned in my copending applications, it may be desirable to use insulating bushings and supports which are provided with internal heating coils so as to prevent wetting of the insulating surfaces exposed inside of the processing chamber.

It is to be understood that where the term "gaseous material" is used in the appended claims, the term is to be construed as covering gaseous material, and gaseous material having liquid or solid particles suspended therein.

This invention has been illustrated only in a general preferred form throughout and it should be understood that it is capable of many and varied modifications without departing from its purpose and scope, and I therefore believe myself to be entitled to make and use any and all of these modifications such as suggest themselves to those skilled in the art to which the invention is directed, provided that such modifications fall fairly within the purpose and scope of the hereinafter appended claims.

What is claimed is:

1. Gaseous phase electric space charge device comprising a perforated emitting electrode, means associated with said emitting electrode for mechanically projecting a stream of physical particles from the surface of said emitting electrode, a collecting electrode and an intermediate grid electrode provided with an opening for the passage of charged physical particles from said emitting electrode through said intermediate grid electrode to said collecting electrode, means for maintaining a rising potential gradient between the respective electrodes causing a drift of electrically charged physical particles from said emitting electrode to said collecting electrode, means for setting up a high frequency field within said electric space charge device and means for circulating gaseous material to be processed through the perforations in said emitting electrode and through said electric space charge device.

2. Gaseous phase electric space charge device comprising an emitting electrode, means associated with said emitting electrode for projecting mechanically a stream of physical particles from the surface of said emitting electrode, an intermediate grid electrode formed to provide a

path for physical particles projected from said emitting electrode, means for maintaining said intermediate grid electrode at such an electrical potential relative to said emitting electrode that certain of the particles leaving the surface of said emitting electrode carry an electric charge and retain this charge in passing through said intermediate grid electrode, a collecting electrode and means for maintaining said collecting electrode at such an electrical potential relative to said emitting electrode and said intermediate grid electrode as to cause a drift of electrically charged particles toward said collecting electrode, said electric space charge device also comprising means for setting up a high frequency field within said electric space charge device and means for introducing gaseous material to be processed into and for withdrawing the processed material from said device.

3. Gaseous phase electric space charge device comprising an emitting electrode, means associated with said emitting electrode for projecting mechanically a stream of physical particles from the surface of said emitting electrode, at intermediate grid electrode formed to provide a path for physical particles projected from said emitting electrode, means for maintaining said intermediate grid electrode at such an electrical potential relative to said emitting electrode that certain of the particles leaving the surface of said emitting electrode carry an electric charge and retain this charge in passing through said intermediate grid electrode, a collecting electrode and means for maintaining said collecting electrode at such an electrical potential relative to said emitting electrode and said intermediate grid electrode as to cause a drift of electrically charged particles toward said collecting electrode, said electric space charge device also comprising means for increasing circulating currents originating in said electrically charged particles by the use of high frequency fields and means for introducing gaseous material to be processed into and for withdrawing processed material from said device.

4. Gaseous phase electric space charge device comprising a rotating electrode, means associated with said rotating electrode for projecting mechanically a stream of physical particles from the surface of said rotating electrode, an intermediate grid electrode formed to provide a path for physical particles projected from said rotating electrode, means for maintaining said intermediate grid electrode at such an electrical potential relative to said rotating electrode that certain of the particles leaving the surface of said rotating electrode carry an electric charge and retain this charge in passing through said intermediate grid electrode, a collecting electrode and means for maintaining said collecting electrode at such an electrical potential relative to said emitting electrode and said intermediate grid electrode as to cause a drift of electrically charged particles toward said collecting electrode, said electric space charge device also comprising means for setting up a high frequency field within said electric space charge device and means for introducing gaseous material to be processed into and for withdrawing processed material from said device.

5. An apparatus for effecting gaseous phase chemical reactions comprising an emitting electrode, means associated with said emitting electrode for projecting mechanically a stream of physical particles from the surface of said emitting electrode, an intermediate grid electrode formed to provide a path for physical particles projected from said emitting electrode, means for maintaining said intermediate grid electrode at such an electrical potential relative to said emitting electrode that certain of the particles leaving the surface of said emitting electrode carry an electric charge and retain this charge in passing through said intermediate grid electrode, a collecting electrode and means for maintaining said collecting electrode at such an electrical potential relative to said emitting electrode and said intermediate grid electrode as to cause a drift of electrically charged particles toward said collecting electrode, said apparatus also comprising means for setting up a high frequency field within said apparatus and means for introducing gaseous material to be processed into and for withdrawing processed material from said apparatus.
- 10 6. Gaseous phase electric space discharge device comprising an emitting electrode, means operatively associated with said emitting electrode for vibrating at least a portion thereof to mechanically project a stream of physical particles from the surface of said emitting electrode, a collecting electrode and an intermediate electrode, said intermediate electrode being provided with an opening for the passage of charged physical particles from said emitting electrode through said intermediate grid electrode to said collecting electrode, means for maintaining a rising potential gradient between the respective electrodes causing a drift of electrically charged physical particles from said emitting electrode to said collecting electrode, means for setting up a high frequency field within said electric space charge device and means for introducing gaseous material to be processed into and for withdrawing processed material from said device.
